UNITED STATES PATENT OFFICE.

JOHN GOOD, OF NEW YORK, N. Y.

COMBING-MACHINE.

1,074,788.

Specification of Letters Patent.

Patented Oct. 7, 1913.

Application filed June 10, 1910. Serial No. 566,154.

To all whom it may concern:

Be it known that I, JOHN GOOD, a citizen of the United States, residing in the borough of Brooklyn, city and State of New York, have invented certain new and useful Improvements in Combing-Machines, of which the following is a full, true, and concise specification.

This invention provides improved apparatus for preparing hemp and other fiber for spinning, and its more prominent object is the reduction of the number of operations required for reducing the fiber from the condition in which it is taken from the bale to the condition of uniformly attenuated, well combed sliver ready to be supplied to the spinning jenny.

Other objects include the saving of power incident to the fewer operations, the saving of floor space, economy of labor in attendance, and various further advantages which will be appreciated by those skilled in this art from the following description and the illustrative drawings which form a part hereof.

Figure 1 of the said drawings is a side elevation of a combing machine such as above referred to, showing one of the several forms in which the invention may be embodied; Fig. 2 is a cross-section thereof on line II—II of Fig. 1; Fig. 3 is an end elevation of the delivery end of the same machine; Fig. 4 is a side elevation of an alternate form, Fig. 5 being a cross-section thereof on line V—V thereof; Fig. 6 is a modification of the forms of Figs. 3 and 4.

The combing machine of this invention is a multi-feed machine, having provisions for the supply of hemp or fiber to be combed at a sufficient number of points and in sufficient quantity at each point to compensate in the body of the resulting combed sliver for the very considerable attenuation that is necessarily incident to a thorough disentangling and straightening of raw or uncombed fiber. The total attenuation necessary for the conversion of raw or bale fiber into combed sliver approximating a spinable character, if imparted thereto in the form of one continuous lap, as for instance by passing the same through any of the existing machines geared over to the necessary high draft ratio, would exceed the length of the individual fibers to such extent as to

interrupt the continuity of the lap as such, 55 and thereby effectually obstruct the practical operation of the machine. The common draft ratio of such hemp combing machines, that is to say, the relative velocities of the high and low speed trains of gill-pins, rarely 60 if ever exceeds the ratio of twenty to one. If increased above this maximum limit, the product sliver tends to become so thin as not to be capable of proper continuous removal from the higher speed chain, while a 65 compensatory increase of the rate of supply to the lower speed chain quickly overloads the pins thereof, the size of which cannot be correspondingly increased because of the obvious mechanical limitations to which they 70 are subject.

The present invention produces a desired total combing effect upon the fiber by subdividing and distributing the combing operation among several simultaneously operating combing heads which may be appropriately termed combing units, since each resembles in principle one of the ordinary hackling-machines having high and low speed gill-pin trains. Each of these units 80 operates upon one of the multiple supplies of fiber, with very high draft and consequently with specially effective combing action, and their several products, each being a lap or sliver more or less thoroughly 85 combed and very considerably attenuated, are collected by an appropriate mechanism and combined into a single sliver, which represents a composite of all, and thus possesses a uniformity of thickness corresponding to 90 the average total of the various products. A considerable number of combing units, three at the least, and preferably six or more, all contributing to the uniformity of the ultimate product, is found to be necessary 95 in order to gain the greatest advantage of the present invention, though the number of units may be somewhat less, when part of the total attenuation is effected by the collecting mechanism, which also constitutes 100 a feature of the invention as hereinafter explained. The invention thus operates to gain uniformity in the product sliver according to a principle resembling the common process of doubling and drawing, but 105 it differs therefrom in that combing is likewise and coincidentally effected upon each of the separate laps and the individual fibers

thereof become thereby distributed longitudinally so as to break up the coextensive termination of adjacent fibers, known as square ends, existing in the raw fiber, and 5 thereby produce an ultimate sliver having its individual fibers disposed in uniformly imbricated relation, which effect, as is well known, cannot be accomplished by doubling and drawing alone. The manner of collecting 10 the combed fibers of each combing unit facilitates this disposition of the fibers, the collection being accomplished by a train or chain of gill-pins common to each of the combing units so that the fibers therefrom 15 will fall or be drawn upon it, in superposed and successively overlapping relation. Such collector train preferably operates as an additional combing instrument, for which purpose it is run at a greater speed than the 20 high speed trains of the combing units from which it collects the fiber so that it will comb and straighten out their respective products. A delivery means serves to remove the fiber from the collector train, and 25 may be geared to exert further draft thereon if desired. It is thus made possible to subject the fiber, by one passage through a machine embodying the present invention, to a thorough combing action without producing 30 an undesired attenuation in the ultimate product.

In each of the exemplifications of the invention herein set forth, the several combing units are identical in construction and mode 35 of operation, for convenience of manufacture, although they might be otherwise. In Figs. 4 to 6, for convenience, only two combing heads are shown, but from the foregoing explanation it will be apparent that these 40 machines are intended to employ many, and preferably six or more of such heads, as desired for the work in hand.

The machines illustrated in the drawings are intended for operation upon raw fiber 45 and for this reason the several fiber-receiving devices thereof are provided with feed-boards 1 upon which the bunches of fiber are intended to be placed in successively overlapping positions to form a continuous 50 fiber-lap, but it will be understood that when the machine is used for fiber that has already been combed or formed into laps, the receiving devices will be modified accordingly. The feed boards are mounted on the 55 upright frame posts 2, and are all inclined in the same direction so that they can be overlapped as indicated, which compact arrangement enables the operator to supply the fiber with the least effort. The bunches 60 of fiber can be quickly laid in place upon them by a horizontal motion, the several boards being open at the sides for this purpose. Each board terminates at its base in an elbow chute or conduit 3, which slightly 65 condenses the lap as it passes through it to

the combing unit mounted immediately below. The combing units are each comprised of two or more trains of gill-pins adapted to operate on the lap according to the principle of the common hackling machine. The gill-pins thereof may be carried by any suitable means, as for instance by cylinders, or by articulated chains, or in any other suitable way, whereby a succession of gill-pins is caused to act on the fiber by 70 continuous movement in a fixed path. 75

In the machine illustrated by Figs. 1 to 3, the pins are carried by rotary cylinders 4 and 5 which are journaled in brackets on the frame posts 2 and revolved by appropriate driving connections from the several inclined shafts 7. The pins are appropriately mounted in each cylinder so that as the cylinder revolves they are projected outwardly on the side thereof that is adjacent the fiber and are withdrawn and housed within the cylinder on their opposite sides, thereby forming a continuous train of moving pins. Cylinders having self-housing pins operating in this manner are well known to builders of hemp and flax working machinery and for this reason the details of their construction is not necessary to be described herein. The upper cylinder 4 constitutes the low speed train of each combing unit, 90 being driven by a worm and worm wheel 6 from the shaft 7. The pins of this train engage the lap directly as it issues from the elbow conduit and conduct and present it to the action of the pins of the lower cylinder 5. This cylinder constitutes the high speed train of the unit, being driven from shaft 7 by bevel gears 8 and its combing effect upon the fiber presented to it by the low speed train will be readily understood by those 95 familiar in this art. The lap is held upon or against the pins of both trains by the inclined lap apron 9 which is supported for 100 that purpose within the side posts 2. The upper face of this apron is curved in general 105 conformity to the path of movement of the pins of the combing unit so as to keep the fiber constantly engaged therewith to a uniform extent of penetration. All of the units 110 are mounted to operate or move their pins in a direction which is inclined toward the delivery end of the machine, reversely to the inclination of the feed boards which supply the fiber to them so that they are also compactly contained in the machine frame. As 115 thus organized the combing units occupy a tandem relation with respect to each other and the collector train. The several driving shafts 7 are bevel-gearred to a common drive-shaft 10 journaled in brackets 11 on the main 120 side girders 16 of the frame, and this shaft is driven through a change speed gearing, indicated somewhat diagrammatically at 12, by the main, transversely journaled power shaft 13. The collector train is formed by 125 130

a chain of articulated gill-pin bars 14 mounted to run on tracks 15 on the inside faces of the side girders 16, although any suitable means for producing a succession or train of pins, moving through a predetermined path, adjacent to the combing units can be employed with similar effect. The chain employed in the present instance is such as is commonly used in hackling machines, and a description of its mechanical construction may therefore be omitted. It is driven at its middle by driving sprocket wheels 17 engaged with both the upper and lower stretches. The shaft of the driving sprockets carries a large sprocket wheel 18 driven by sprocket chain 19 from the power shaft 13. At the end of its lower stretch the collector chain passes over a notched idler wheel 14^a by which it is elevated to the beginning of the track of the upper stretch and in moving along this upper stretch its pins are maintained in a forwardly inclined position which is gradually diminished as they approach the delivery end, and finally 25 reversed as they move downwardly into the forward end of the lower stretch. The control of the inclination, or rake, of the collector pins in this manner is accomplished by means of the dogs on the ends of the gill-bars which run in appropriate cam-grooves adjacent the tracks 15. The dogs appear in Fig. 2, and their construction and mode of operation are quite well-known to persons familiar with this art.

When the machine is built with a sufficient number of combing units all contributing to the collector train and each producing the desired degree of combing effect, the collector chain 14 may be driven at a speed substantially equal to that of the high speed trains of the combing units so that the combed fibers therefrom will be deposited upon the collector chain without further combing or further attenuation, in which case the chain will serve solely as a collector to combine the products of the several units and convey them as a composite sliver to the delivery head, which removes them from the chain. It is preferred, however, that the collector chain shall also contribute to the combing action of the machine, for which purpose it is driven at a higher speed than the cylinders 5 and engages and draws the fiber therefrom with a coincident combing effect and further attenuation. Each lap supplied through the elbow conduits 3 is thus subjected to successive combing actions, two in the present case, as it moves from the conduit to the delivery head, the last 50 combing action being effected by a member, the chain 14, which is common to all of the laps, and combines them. As the pins of the combined collector and combing chain approach the delivery head, the reversal of 55 their normal forward inclination enables

them to leave the lap by withdrawal in an endwise direction.

The delivery head, stationed at the end of the upper stretch of the collector chain 14, comprises a system of rollers appropriately journaled in the side frames and carrying two apron belts, 21 and 21^a, of leather, which run in contact with each other from a point at about the level of the chain 14 to the top of the head. The fiber on the 75 chain is directed into the nip of these two belts by the guide board 14^b and is thereby carried upwardly, becoming deposited upon a short conductor chute 22 from whence it passes through the calender rolls 23 into the 80 sliver can. The system of delivery-head rollers is driven by a belt or chain 24 from the power shaft and the calender rolls, by a suitable belt connection 25 from one of the 85 roller shafts. The mechanical details of the delivery head, like the collector chain 14, are also well known to this art. When combined in the present invention, the speed of its belts is adjusted to that of the chain 14 so that it exerts more or less draft upon the 90 composite sliver according to the body of the latter, and when the number of combing units is sufficient to form a composite sliver on the collector chain of greater thickness or body than is necessary or required for the 95 next succeeding operations, the draft of the delivery head may be correspondingly increased to reduce such sliver to a proper or desired transverse dimension.

Referring now to Figs. 4 and 5, it is apparent that the principle of construction and operation is the same as the machine above described. The gill-pin trains of the combing units, however, are formed by articulated chains 26 and 27, like the chain 14, instead of by gill-pin cylinders, and for that reason the pins thereof have the advantage that they may travel in straight paths and engage the fiber for a greater distance. The upper and lower chains are shown as being 100 the same in size and length, being carried on the notched wheels 28 and 29 respectively, which are journaled in the side frames. Tracks and cam ribs, not shown, are also provided to guide the movement of the pins 105 and the rake thereof. A lap-apron 30, which in this form is a flat board, holds the fiber at uniform penetration on the pins. The slow speed chain 26 may move with its pins raked forwardly during the early part 110 of their operative path to give them positive engagement with the fiber, but as they approach the higher speed chain 27, their rake is gradually reversed, as indicated, in order to keep the fiber from being pulled too readily from them by the action of the lower chain. Power is applied to the chains through their lower carrier wheels, the drive of one being through a worm wheel and 115 worm from the shaft 7, and the other 120

125 130

through bevel gears from the same shaft. By substitution of different driving members, the relative speeds of the two chains, that is to say their draft, ratio can be adjusted as desired. The multiple feeds of fiber led to this form of machine, will be combed in each of the combing heads, of which there should be several, and on engaging the collector chain 14 will be again 10 and further combed, producing a combed sliver on the said chain which is removed in the obvious manner by the delivery head and deposited in the sliver can.

In machines built as above described, the 15 draft ratio of the members of each combing unit is made sufficiently high to perform the greater part of the combing and imbricating action necessary while the pins of the collector chain perform the remainder. The 20 draft ratio of the members of the combing units may, for instance, be 80 or 90 to 1, which will be sufficient to dissipate square ends in manila hemp and clean and disentangle the snarled and matted fibers with a 25 fair degree of thoroughness, and if the collector chain have a draft ratio of say 3 to 1 to the combing units, the additional combing and imbricating action thereby effected will produce a product still more thoroughly 30 combed. The attenuation of the lap incident to the high draft employed in each unit will necessarily call for a sufficient rate of fiber supply to form a removable composite sliver on the collector chain, and this is accomplished by the multiplicity of contributing heads or combing units as above explained; from all of which it will be observed that this invention provides a means 35 for attaining, in a single continuous operation, any degree of combing or hacking effect that may be desired in the preparation of the fiber for spinning, although the invention, it will be understood, is not in any way limited by the extent of combing which 40 it is called upon or constructed to perform in a single passage of fiber through it.

Fig. 6 shows the same arrangement of high and low speed chains constituting the combing units, as shown in Figs. 4 and 5, 45 but in this form of machine the fiber from the high speed combing unit chains is positively withdrawn by a pair of rollers 31 and by them deposited upon the collector chain 14; otherwise the machine is the same as the preceding. The rollers 31 are driven by bevel gearing 32 from the shaft 10.

In all of the above forms the combing trains of the several units operate in an inverted position, which is particularly suitable for high draft operation and hence preferred, since gravity is thus made to assist in the transfer of the fiber to the collector chain and facilitates its deposit upon the latter in longitudinal and parallel positions 60 without tendency of looping or bunching,

and moreover, the arrangement permits the lower portions of the lap, which are in contact with the lap apron 9 on the under side of the body of the lap, to engage first with the pins of the collector chain so that, if 70 such portions have not received uniform combing in the combing unit, they are compensated by the collector chain.

The driving and speed-changing connections for the several moving parts as illustrated in the drawings are to be understood as intended to perform the functions above ascribed to them. The mechanical details of their construction form no part whatever of the present invention, and for that reason 80 are not specifically shown. It is preferred, however, that such gearing be of a type adapted to be changed or regulated to give varying speed to the several trains of pins and the delivery head, so that the machine 85 as a whole will be susceptible of adjustment to fibers of different lengths and character and to different results.

It will be understood by those skilled in this art that the machines above described 90 are not limited in respect of the size or proportion of their parts or pins, nor of their draft ratio, nor to the details of the mechanical assemblage, and that various omissions, substitutions and alterations in the 95 form and operation may be made without departing from the invention. It will be observed, moreover, that the several combing units thereof can be used with different kinds of fiber and with different draft ratios 100 and sizes of gill-pins or with such other changes in relative proportions as may adapt it for the most effective operation upon the kind or kinds of fiber with which it is to be used.

I claim:

1. A combing machine adapted to receive three or more separate, continuous supplies of the fiber to be combed, a corresponding number of combing-units each composed of high and low speed gill-pin trains respectively operative with a combing effect on each of such separate supplies, in combination with means for collecting the products of all said combing-units and combining the 110 same into a single sliver.

2. A combing machine, comprising three or more feed-boards adapted for the forming of bunches of raw fiber into continuous laps of fiber, a combing-unit for each such lap, each unit comprising a gill-pin train for conducting the lap and a higher speed train coöperating therewith with combing effect upon the lap, in combination with means common to all the said combing-units for 115 combining their combed products into a continuous, composite sliver.

3. A combing machine, comprising a plurality of feed-boards terminating in elbow conduits, a combing-unit operative upon the 120

fiber issuing from each such conduit and mechanism common to each unit for collecting and combining the fiber combed thereby.

4. A combing machine having a plurality of feed-boards inclined in the same direction and adapted for the formation of bunches of raw fiber placed thereon into continuous fiber-lap, a combing-unit operative upon each lap at the base or end of its feed-board and a common conveyer mechanism adapted to collect and combine the combed fiber of all the combing units.

5. A combing machine, comprising a plurality of combing-units, each comprising high and low-speed gill-pin trains, means for supplying fiber to be combed to said units and conveyer and collector means mounted to travel beneath said combing-units for collecting and combining the combed fiber from each of them into a single sliver.

6. A combing machine, comprising a gill-pin train forming a traveling conveyer member, a plurality of combing-units arranged in tandem relation with respect to the path of movement of said conveyer member and means for operating said combing-units whereby they deliver their respective combed products in superposed relation to said member.

7. A combing machine, comprising a plurality of suitable means for forming bunches of fiber into continuous fiber-laps and individual combing-pin trains operative respectively on each of said laps to comb the same, in combination with a train of collecting gill-pins common to each of said first mentioned trains for collecting the combined fibers therefrom as a composite sliver of the several fiber-laps.

8. A combing machine, comprising a plurality of feed-boards suitable for receiving bunches of fiber to form the same into continuous fiber-laps, a plurality of means for conducting said laps from the feed-boards, a plurality of combing-pin trains for combining them, and a train of collecting pins common to each of said combing-pin trains and adapted to deliver the fibers combed thereby as a single sliver.

9. A combing machine, comprising in combination, a plurality of combing-units each composed of high and low speed gill-pin trains, and gill-pin conveyer mechanism common to said units adapted for collecting the combed fibers therefrom and delivering the same as a composite sliver.

10. In a combing machine, a plurality of means for receiving and forming bunches of fiber into continuous fiber-laps, a corresponding number of combing-units respectively operative upon each of said laps and adapted to deliver combed fiber product thereof upon a conveyer member, in combi-

nation with a moving train of pins constituting said conveyer member.

11. In a combing machine, a plurality of combing-units each adapted for operation upon a separate fiber-lap and organized to deliver their respective products to a conveyer member, a moving train of pins constituting such conveyer member and means for driving the same with draft over said combing units.

12. In a combing machine, the combination with a moving train of gill-pins, of a plurality of combing-units each adapted for combing operation independent of the others and delivering their respective combed products to successive points along the receiving stretch of said moving train.

13. The combination in a combing machine, of a plurality of low-speed gill-pin trains, a corresponding number of higher speed trains respectively coöperating therewith, and a single train of combing pins common to all said last mentioned trains and means for moving the same at a still higher speed.

14. The combination in a combing machine, of three or more combing-units each comprising a gill-pin train having combing effect upon the fiber passing therethrough, a common collecting train for said units exerting draft on the fiber received from said units and a delivery-head for the fiber on said common collecting train exerting draft thereon.

15. A combing machine having organized therein a plurality of feed-boards and a single sliver-delivery head, in combination with means for combing and simultaneously conducting the fiber from each feed-board to the delivery-head, said means comprising a plurality of gill-pin trains operative with combing effect upon the fiber moving from each feed-board at two or more successive points in the passage of said fiber to the delivery-head.

16. A combing machine having organized therein a plurality of means for receiving fiber, and a single sliver delivery combined with means for separately conducting the fiber introduced at each receiving means to the said delivery, said means comprising a series of trains of gill-pins, each train transmitting its fiber-lap direct to the succeeding train in the series and each succeeding train exerting draft upon the lap taken thereby.

17. A combing machine having organized therein, a plurality of means for receiving fiber and a single sliver-delivery head, in combination with means for conducting the fiber introduced at each receiving means to the said delivery head, said means comprising a series of trains of gill-pins, each train transmitting its fiber lap directly to a succeeding train in the series and the last train in the

series being common to all the said succeeding trains and adapted to conduct the combed fibers thereof to the said sliver delivery, each succeeding train and the said last train 5 exerting draft on the fiber.

18. In a combing machine, the combination with a plurality of combing units each comprising high and low speed gill-pin trains, the pins thereof being pointed downwardly and a conveyer member traveling beneath said units and common to all of them.

19. In a multi-feed combing machine, a plurality of combing-units, each having 15 high and low speed gill-pin trains and disposed in downwardly pointed position to

move in a path forwardly and downwardly inclined with respect to the movement of the collector member and a collector member common to all of said units.

20

20. In a combing machine, the combination of a collector combing-pin chain, a plurality of combing-units arranged in tandem relation along said chain and delivering fiber thereto and a delivery-head for removing the fiber from said combing chain.

25

In testimony whereof, I have signed this specification in the presence of two witnesses.

JOHN GOOD.
